Inventor

CHARLES S. FARRER

By Watson E. Coleman

Attorney

UNITED STATES PATENT OFFICE.

CHARLES S. FARRER, OF DUNMORE, PENNSYLVANIA.

TURBINE.

1,283,485.

Specification of Letters Patent.

Patented Nov. 5, 1918.

Application filed September 22, 1917. Serial No. 192,759.

To all whom it may concern:

Be it known that I, CHARLES S. FARRER, a citizen of the United States, residing at Dunmore, in the county of Lackawanna and State of Pennsylvania, have invented certain new and useful Improvements in Turbines, of which the following is a specification, reference being had to the accompanying drawings.

10 This invention relates to an improved turbine, and has for its primary object to provide a turbine construction which is particularly designed for use in connection with the blower constituting the subject-matter 15 of my issued patent, No. 1,222,274, dated April 10, 1917.

It is an additional object of the invention to provide a one-piece steam ring having separate steam receiving chambers of the 20 type disclosed in the patent above referred to, an improved turbine wheel mounted on the fan shaft and upon which steam is delivered from one of the chambers through spaced jet orifices, the turbine wheel and 25 blades being so constructed and associated with the steam ring that a maximum driving impulse is obtained in the impingement of the steam jets upon the turbine blades.

And it is an additional detail object of 30 the invention to provide improved means for exhausting the steam after it has acted upon the turbine blades, whereby its condensation within the draft nozzle is obviated.

With the above and other objects in view, 35 my invention consists in the novel features of construction, combination and arrangement of parts to be hereinafter more fully described, claimed, and illustrated in the accompanying drawings, in which,

40 Figure 1 is a longitudinal sectional view illustrating the preferred embodiment of my improved turbine;

Fig. 2 is a sectional view taken on the line 2—2 of Fig. 1;

45 Fig. 3 is a fragmentary side elevation of the turbine wheel;

Fig. 4 is a detail fragmentary plan view of the wheel;

Fig. 5 is an enlarged detail section taken 50 on the line 5—5 of Fig. 1;

Fig. 6 is a front end elevation;

Fig. 7 is a section taken on the line 7—7 of Fig. 1;

Fig. 8 is an enlarged fragmentary sectional view through the steam ring; 55

Fig. 9 is a section taken on the line 9—9 of Fig. 8;

Fig. 10 is a detail fragmentary perspective view of the turbine wheel rim.

Referring in detail to the drawings, 5 60 designates the blower nozzle which may be mounted and secured in the furnace wall in contiguous relation to the grate in any usual or approved manner. This nozzle at its outer end or mouth is diametrically enlarged 65 to form an annular shoulder 6 thereon and the forwardly projecting flange 7.

The steam ring generally indicated by the numeral 8, consists of a single, annular, metal casting which is hollow and centrally 70 divided by a horizontal, annular wall 9 into the inner and outer annular steam receiving chambers 10 and 11 respectively. As illustrated, these chambers are of substantially 75 the same capacity, but it will be understood that if desired, the partition wall 9 may be so located that the outer chamber will be of greater capacity than the inner chamber or vice versa.

The steam ring 8 is provided with a plurality of equidistantly spaced, threaded openings 12 which communicate with the outer steam chamber 11 of the ring and open upon the inner face of said ring. Detachable jet nipples 13 have threaded engagement in these openings. It will be noted that the openings 12 and consequently the bores of the jet nipples, are angularly disposed with respect to the longitudinal axis of the blower nozzle so that the several 90 steam jets will be delivered or injected inwardly through the nozzle in convergent relation to a point in the axial line of the nozzle at the inner end of the latter.

The annular ring 8 at the juncture of its 95 inner side wall with the inner annular wall of the ring, is provided with a convex face indicated at 14, which merges into the concave inner face 16 of an annular flange 15 formed upon the ring and projecting laterally therefrom. An annular rib or flange 17 is formed upon the inner wall of the ring

8 in spaced relation to the convex face 14 of said ring. Steam jet orifices, indicated at 18, are formed through the ring wall and open at their outer ends upon the convex 5 ring face 14, the inner ends of these orifices communicating with the steam chamber 10. As shown in Fig. 8, these orifices extend through the ring wall at an angle of substantially 45° with respect to the axis of the 10 nozzle, and as shown in Fig. 9, they are also obliquely inclined circumferentially of the steam ring. The steam delivery jet orifices just described are so arranged to obtain the most effective action of the steam jets upon the 15 turbine wheel which operates the blower fan. This turbine wheel will presently be fully described in detail.

The cylindrical, longitudinally extending wall 19 is integrally formed with the outer 20 side wall of the steam ring 8 and is of greater diameter than the steam ring. Upon the inner face of this wall 19, spaced seats 20 are formed, upon which the base 21 of a bearing pedestal is engaged and securely fixed by means of the bolts 22 extending through said seats and the wall 19. The converging standards 23 of the bearing pedestal are integrally connected to one half 25 of an elongated bearing 24, the other half 25 of said bearing being securely, though removably fixed to the bearing section 24 by bolts 26. The cap bearing plate 25 is preferably constructed in a plurality of sections, as clearly seen in Fig. 1 of the drawings. 27 30 designates the fan shaft which is mounted in the bearing and extends beyond the opposite ends thereof. Bearing sleeves 28 are engaged upon this shaft between the same and the bearing sections 24 and 25. These 35 sleeves are each likewise formed in two sections as shown in Fig. 2. The bearing section 24 is formed with a longitudinally extending, oil receiving groove 29, and the upper bearing sections 25 as well as the lower bearing section 24 are formed with internal, 40 circumferential channels 30 communicating with said groove. Each of the upper sleeve sections 28 is centrally grooved or channeled, as at 31, said groove at its medial 45 portion extending entirely through the sleeve section to expose the periphery of the shaft 27. Rings 32 are loosely engaged in the grooves or channels 31 and around the lower sleeve section 28. A suitable lubricating oil is supplied to the internal groove 30 of the central bearing section 25 through 50 the medium of a pipe or tube 33 which extends through an opening in the wall 19. It will thus be seen that the lubricating oil 55 which collects in the groove 29 of the lower bearing section is continually supplied to the periphery of the shaft 27 by the rings 32.

The annular rim 34 of the turbine wheel 60 is connected by a plurality of radially disposed arms 35 to a central hub 36 which is

adjustably secured on the inner end of the fan shaft 27 by a set screw 37. The outer face of the rim 34 of the turbine wheel is curved, as at 38, and upon this curved face the spaced blades or vanes 39 are formed. 70 These blades are obliquely inclined across the face of the wheel as seen in Fig. 4, and gradually decrease in width longitudinally from one of their ends to the other. The wider ends of the blades 39 which are opposed to the concave face 16 on the flange 15 of the steam ring, project outwardly from the peripheral face of the wheel rim, while the reversely curved medial portions of the blades opposed to the convex face 14 of the 80 steam ring, gradually merge into the plane of the outer face of the turbine wheel. The narrower end portions of the blades extend in parallel relation to the axis of the wheel and are flush with the outer face of the 85 wheel rim at its inner edge, as clearly shown in Fig. 10 of the drawings. It will be observed that the concavely curved medial portions of the turbine blades are opposed to the outer open ends of the jet orifices 18 90 of the steam ring. As will be seen from reference to Fig. 9 of the drawings, these orifices will deliver this steam on a substantially tangential line with respect to the wheel, partly against the blades or vanes 95 39 and partly upon the rim face of the wheel at the base of the wider end portions of the blades. I have found that by means of this construction, the turbine will be driven at a very high speed with a minimum of frictional wear and also with a relatively small consumption of steam. Preferably, it is desirable to prevent the condensation of the steam and the collection of water therefrom within the steam nozzle and, to this end, I 100 provide a hollow, annular, exhaust receiving ring 40, the chamber 41 of which at one side of the ring is relatively narrow and of a width substantially equivalent to the width of the wider ends of the turbine blades 39. 110 This ring is securely fixed upon the side face of the flange 15 of the steam ring by means of a plurality of bolts indicated at 42. A discharge or drain pipe 43 is connected to the lower side of the exhaust ring 40 and extends through a suitable packing chamber 44 provided upon the wall of the nozzle 5. It is to be noted that the inner 115 wall of the exhaust receiving ring 40 coacts with the turbine wheel at the egress side thereof and effectually prevents the axial displacement of this wheel in one direction with respect to the steam ring, and thereby retains the blades on the rim face of the wheel in proper relation to the recessed face 120 of the steam ring. 125

Upon the outer end of the shaft 27, the fan indicated at 45 is adjustably secured by means of a set screw 46. This fan may be of any approved conventional form, and by 130

locating the fan exteriorly of the steam ring and outwardly of the bearing pedestal for the fan shaft, should the fan break or be otherwise rendered temporarily inoperative, 5 it can be readily removed from the fan shaft and repaired, or another fan substituted therefor. Also, access may be readily had to the set screw 37 for the turbine wheel and said wheel adjusted to compensate for wear 10 and properly dispose the turbine blades with respect to the contiguous face of the steam ring.

An annular cap plate 47 is provided upon its outer edge with a continuous, laterally 15 projecting flange 48 for engagement exteriorly upon the forward end of the cylindrical wall 19, to which wall said flange is secured by means of the screws indicated at 49. The plate 47 is provided upon its inner edge with an inwardly and outwardly 20 extending annular wall 50 which constitutes a casing for the fan 45. A door 51 is hingedly mounted upon the plate 47 and is adapted to close the outer open side of the 25 casing 50, suitable latch means being provided to hold said door in its closed position. Preferably, a damper or valve plate, indicated at 52, is mounted upon the plate 47 and is provided with openings therein 30 which are adapted to be brought into coinciding relation with air openings in the plate 47 by a rotation of said valve plate. Thus, air may be admitted to the nozzle under the action of the steam jets issuing from the 35 nipples 13 when the door 51 is closed.

The air drawn in through the fan casing, exerts a back pressure against the blades of the fan or propeller, and one of the particular objects and purposes of the specific 40 construction of the turbine hereinbefore described is to counteract this back pressure which would otherwise result in a longitudinal thrust of the fan and turbine shaft and create excessive friction and wear upon the 45 shaft collars and bearing. This result is accomplished by providing the turbine wheel or rim and the blades thereof with the outwardly curved section, upon which a portion of the jets from the steam ring is directly 50 discharged. This steam pressure on the curved rim face and the blades tends to thrust the turbine shaft inwardly in a longitudinal direction, and exactly counterbalances the thrust in the opposite direction, 55 due to the back pressure of the air against the fan or propeller blades. The remaining pressure from the steam jets, strikes the blades on the horizontal portion of the turbine rim or wheel, and drives or rotates the 60 turbine to operate the fan. Thus, it is seen that the operation is properly balanced by the reverse end thrusts on the turbine and the fan. Any desired amount of propelling power for the turbine may be obtained by 65 simply extending the horizontal portion of

the turbine rim or wheel and enlarging the steam jet orifices in the ring proportionately.

Steam is supplied to the inner chamber 10 of the ring 8 through the pipe 61 and to 70 the outer chamber of said ring through the pipe 62. The supply of steam to these two ring chambers may be independently controlled as in my prior patent hereinbefore referred to.

75 From the foregoing description, taken in connection with the accompanying drawings, the construction, manner of operation, and several advantages of my invention will be clearly and fully understood. By means 80 of a relatively simple addition to the invention disclosed in my prior patent, I obtain both a fan and a steam blower, either of which may be operated independently of the other to create the requisite air draft beneath the fuel bed. Ordinarily steam will be supplied to the inner steam chamber only 85 for the rotation of the turbine, whereby air is forced through the nozzle by means of the fan. If the fan breaks down or the turbine 90 wheel requires repairs, these parts may be removed or the fan door closed without removing the damaged parts, and the operation of the blower continued by admitting steam to the outer chamber 11, the damper 95 or valve plate being opened as above explained so that the steam jets from the nozzles 13 will continue the draft of air through the nozzle and the apparatus will not be rendered temporarily useless. It will be observed 100 that I have provided a very compact arrangement and assemblage of the several elements. The steam ring and turbine, the fan, the casing therefor, and the valve plate all may be removed together from the nozzle mouth simply by removing the bolts 64. Also, it is to be observed that the fan, as 105 well as the turbine wheel, may be readily adjusted or access had thereto for the purpose of repairing the same.

110 While I have above referred to the turbine constituting the subject matter of the present application as being used in connection with a furnace blower, it is, of course, apparent that the improved features of the 115 turbine construction can also be adapted to many other analogous uses. Therefore, it will be understood that the foregoing description and drawings are merely illustrative of one adaptation of the invention, for which it is 120 primarily designed, and in which use the turbine has been found in practice to give effective and reliable service.

125 While I have herein shown and described the preferred construction and arrangement of the several elements employed, it is to be understood that the device is susceptible of considerable modification therein and I, therefore, reserve the privilege of adopting all such legitimate changes as may be fairly 130

embodied within the spirit and scope of the invention as claimed.

Having thus fully described my invention, what I desire to claim and secure by Letters

5 Patent is:

1. In combination, a hollow steam receiving ring, a turbine wheel having an annular rim provided with spaced blades upon its outer face, said blades gradually decreasing 10 in width to one of their ends and merging into the rim face, said steam ring having its wall recessed to receive the rim of the turbine wheel, and provided with means for the delivery of steam jets partly against the 15 blades and partly against the face of the turbine wheel.

2. In combination, a hollow steam receiving ring, a turbine wheel having an annular rim provided upon its peripheral face with 20 spaced blades having adjacent portions longitudinally curved in relatively opposite directions, said ring having an exterior surface portion corresponding to the curvature of said blades, and being provided with 25 spaced steam jet orifices to deliver steam jets tangentially upon the blades of the turbine wheel.

3. In combination, a hollow steam receiving ring, a turbine wheel having an annular 30 rim provided upon its peripheral face with spaced blades having adjacent portions longitudinally curved in relatively opposite directions and each gradually merging at one of its ends into the face of the wheel rim, 35 said ring having an exterior surface portion of corresponding curvature to the turbine blades and provided with spaced jet orifices to deliver steam jets against the blades in tangential relation to the turbine wheel.

4. In combination, a hollow steam receiving ring, a turbine wheel having an annular rim provided upon its peripheral face with 45 spaced blades having adjacent portions longitudinally curved in relatively opposite directions, each of said blades at one of its ends tapering longitudinally and gradually merging into the peripheral face of the wheel rim, said ring having an exterior surface portion of corresponding curvature to 50 said blades and provided with spaced jet orifices to deliver steam jets upon the blades in tangential relation to the turbine wheel and partly against the rim face of the wheel.

5. In combination, a hollow steam receiving ring, a turbine wheel having a rim provided upon its peripheral face with spaced blades having adjacent portions longitudinally curved in relatively opposite directions, each of said blades tapering at one 60 of its ends and merging into the peripheral face of the wheel rim, the inner wall of the steam ring having its exterior surface recessed to receive the turbine rim and blades and the face of said recess corresponding in 65 curvature to said blades, said steam ring

being further provided with spaced jet orifices to deliver steam jets partly upon the blades in tangential relation to the turbine wheel and partly against the rim face of the wheel.

6. In combination, a hollow steam receiving ring, a turbine wheel having an annular rim provided with an outwardly flaring edge portion and spaced blades on the outer face of the rim gradually increasing in width 75 upon the flaring edge of the rim, the steam ring having a plurality of jet delivery orifices to discharge steam in tangential relation to the turbine wheel upon the rim thereof at the base of the flaring edge portion 80 of said rim.

7. In combination, a hollow steam receiving ring, a turbine wheel having an annular rim provided with an outwardly flaring edge portion and spaced blades on the outer face 85 of the rim gradually increasing in width upon the flaring edge of the rim, the steam ring having a plurality of jet delivery orifices to discharge steam in tangential relation to the turbine wheel upon the rim thereof at the base of said flaring edge portion, 90 said steam ring being provided upon one of its side faces with an annular flange projecting over the flaring edge of the wheel rim and the ends of the turbine blades. 95

8. In combination, a hollow steam receiving ring, a turbine wheel having an annular rim provided with an outwardly flaring edge portion and spaced blades on the outer face of the rim gradually increasing in width 100 upon the flaring edge of the rim, the steam ring having its wall recessed to receive the opposite edge portion of the wheel rim and the blades and the latter edges of the blades merging into the peripheral face of the rim, 105 said steam ring having a plurality of jet delivery orifices to discharge steam in tangential relation to the turbine wheel upon the rim thereof at the base of the flaring edge portion of said rim, said steam ring 110 being provided upon one of its side faces with an annular flange extending over the flaring edge of the wheel rim and the ends of the turbine blades.

9. In combination, a hollow steam receiving ring, a turbine wheel having a multi-bladed rim juxtaposed to the steam receiving ring, said ring having a plurality of jet orifices in its wall for the delivery of steam jets against the blades of the turbine wheel, 120 and a steam exhaust receiving member fixed to the steam ring and into which the steam is directly discharged from the egress side of the wheel, said member coacting with the turbine wheel to prevent axial movement of 125 said wheel relative to the steam ring.

10. In combination, a hollow steam receiving ring, a turbine wheel having a multi-bladed rim arranged in juxtaposed relation to the steam ring, said ring having a plu- 130

- rality of steam jet orifices in its wall for the delivery of steam against the blades of the turbine wheel, and a relatively stationary exhaust receiving member into which the steam is directly discharged from the egress side of the wheel, said member coacting with the rim of the turbine wheel and preventing axial movement thereof with relation to the steam ring.
11. In combination, a hollow steam receiving ring, a turbine wheel having a multi-bladed rim arranged in juxtaposed relation to the steam ring, said ring having a plurality of steam jet orifices in its wall for the delivery of steam against the blades of the turbine wheel, and a continuous annular exhaust receiving member fixed to one side of the steam ring and into which the steam is directly discharged from the egress side of the wheel, said member having a part coacting with the rim of the turbine wheel to hold the latter against axial displacement relative to the steam ring.
12. In combination, a hollow steam receiving ring, a turbine wheel having an annular rim rotatable within the steam ring and disposed in the plane of the inner wall of said ring, said rim having spaced blades on its outer face extending longitudinally of the ring and having contact with the wall thereof, said ring being provided with a plurality of jet delivery orifices for the delivery of steam against the blades of the turbine wheel.
13. In combination, a hollow steam receiving ring, a turbine wheel having an annular rim provided with an outwardly flaring edge portion and spaced blades extending longitudinally of the ring and having curvilinear portions extending upon the flaring edge portion of the rim, the steam ring having a plurality of jet delivery orifices to deliver steam against said blades at a point intermediate the ends thereof.
14. In combination, a hollow steam receiving ring, a turbine wheel having an annular rim disposed in the plane of the inner wall of said ring, said rim being provided with an outwardly flaring edge portion and spaced blades extending obliquely on the outer face of the rim and having curvilinear portions on the flaring edge of the rim, the steam ring being provided with a plurality of jet delivery orifices for the delivery of steam upon the rim face of the turbine wheel at the base of the flaring edge portion thereof.
15. In combination, a hollow steam receiving ring, a turbine wheel having an annular rim rotatable within said ring and disposed
- in the plane of the inner wall of the steam ring, said rim having an outwardly flaring edge portion and spaced blades extending obliquely across the outer face of the rim and having curvilinear portions gradually increasing in width to the egress side of the rim, said latter portions of the blades being disposed upon the flaring edge of the rim, the steam ring having a plurality of jet delivery orifices to discharge steam in tangential relation to the turbine wheel upon the rim face thereof and intermediate of the ends of said blades.
16. In combination, a hollow steam receiving ring, a turbine wheel having an annular rim and blades upon the outer face of the rim, said rim being rotatably mounted within the ring and disposed in the plane of the inner wall of said ring, the egress side of the turbine wheel being flush with one side of the ring, and an exhaust receiving member secured to the latter side of the ring to directly receive the exhaust steam from the turbine wheel.
17. In combination, a hollow steam receiving ring, a turbine wheel having an annular rim and blades upon the outer face of the rim, said rim being rotatably mounted within the ring and disposed in the plane of the inner wall of said ring, the egress side of the turbine wheel being flush with one side of the ring, and an exhaust receiving member secured to the latter side of the ring to directly receive the exhaust steam from the turbine wheel, said member having a part coacting with the rim of the turbine wheel to prevent axial movement of said wheel in one direction with respect to the steam ring.
18. In combination, a hollow steam receiving ring, a turbine wheel having an annular rim and blades upon the outer face of the rim, said rim being rotatably mounted within the ring and disposed in the plane of the inner wall of said ring, the egress side of the turbine wheel being flush with one side of the ring, and a hollow annular exhaust receiving member open upon one side and secured to the latter face of the steam ring to directly receive the exhaust steam from the turbine wheel, the inner wall of said annular member coacting with the rim of the turbine wheel to prevent axial movement of said wheel in one direction with respect to the steam ring.

In testimony whereof I hereunto affix my signature in presence of two witnesses.

CHARLES S. FARRER.
